NOTE-SHEET-CENTERING MECHANISM FOR PLAYER-PIANOS.

1,243,330.

Specification of Letters Patent.

Patented Oct. 16, 1917.

Original application filed February 5, 1916, Serial No. 76,387. Divided and this application filed June 29, 1916. Serial No. 106,673.

To all whom it may concern:

Be it known that we, ERNST D. MOORE, a citizen of the United States, and STANLEY L. FISHER, a subject of the King of Great Britain, both residing in Saybrook, county of Middlesex, and State of Connecticut, have invented certain new and useful Improvements in Note-Sheet-Centering Mechanism for Player-Pianos, of which the following is a full, clear, and exact description.

This invention relates to note sheet centering mechanism for player pianos, and more particularly to mechanism for centering the music roll with respect to the tracker bar.

One of the primary objects of the invention is to furnish simple, conveniently actuated means for centering the music roll automatically when it is placed between its supporting spindles in the spool box so that the perforations of the note sheet will be in line with the corresponding tracker openings. More particularly it is aimed to provide supporting and centering mechanism for the music roll, which is equally effective with various makes of rolls, and which will center the roll relatively to the tracker bar irrespective of the depth of the sockets in the roll heads and the distance between the bottoms of these sockets. Our improved centering mechanism will also be effective with rolls of different overall length, and consequently by our invention the range of utility of the piano player is very much increased.

Another object of the invention is to provide a note sheet centering mechanism of the kind indicated in which no adjustment is necessary to adapt the mechanism to different kinds or sizes of rolls.

In the centering of music rolls relatively to the tracker bar, the depth of the sockets in the roll heads has heretofore been a very important factor. The music roll spindles usually bottom in these sockets, and hence the spindles will not properly center a roll in which the sockets do not have the required dimensions and the required relation to the music roll as a whole. It is a rather difficult matter to form the sockets with the required accuracy, so that in rolls of the same make there is often sufficient inaccuracy

to prevent proper centering; but, in any case, if the piano player is adapted to rolls of one make, it may not be adapted to rolls of another pattern.

Our invention is based on the centering of the rolls relatively to the tracker bar by means of the overall length of the former. We have discovered that owing to the fact that practically all of the music rolls found on the market have symmetrically formed heads, and as the outer faces of these heads either lie at equal distances from the center of the note sheet or can be made to do so (where there is a movable head or end flange), it is possible to center rolls of different types in a self-playing piano by positioning such rolls by means of their end faces rather than by spindles which engage the bottoms of the sockets. By using this system, the mechanism may be very simple, both in manufacture and in use, and many different kinds of rolls can be used very successfully in the same piano player.

To these and other ends, the invention consists in the novel features and combinations of parts to be hereinafter described and claimed.

In the accompanying drawing,

Figure 1 is a front elevation of note sheet centering mechanism embodying our invention, showing the music roll in the playing position;

Fig. 2 is a rear elevation of the parts shown in Fig. 1, showing the roll-holding levers in the position which they assume when the roll is removed;

Fig. 3 is a top plan view of the parts shown in Figs. 1 and 2; and

Figs. 4 and 5 are detail views of the music roll spindles.

In the embodiment shown, the spool box 10 is of the usual type and supports the customary tracker bar 11 in the ordinary manner. The tracker bar may be fixed in position by screws 12, as shown, or, in some cases, may be so mounted as to permit lengthwise adjustment. The music roll 13 carrying the note sheet 14 is mounted above the tracker bar in the customary location by means of spindles 15, 16. We have not considered it necessary to illustrate the usual take-up spool which is located in the customary manner beneath the tracker bar. The

spindle 15 is in the nature of an enlarged hub on a stem 15^a, said spindle or hub being located at the inner face of the box wall and guided for lengthwise movement in a bushing 20 in said wall, as shown at Fig. 4. At its inner end, the spindle 15 is provided with a laterally projecting flange or collar 21 having a vertical face disposed toward the adjacent music roll head 13^a. Projecting 10 inwardly from the collar 21 is a centering projection or boss 22 with an inclined periphery adapted to enter a correspondingly shaped but larger recess 23 in the roll head 13^a. The arrangement is such that while the 15 vertical inner surface on the collar 21 makes contact with the end face of the roll head 13^a, the boss 22 is of such size and shape as not to bottom in the recess or socket 23. The spindle 16 is generally similar to the 20 spindle 15, being mounted on a stem 16^a and guided for endwise movement in a bushing 24 of the box wall. Near the inner end of the spindle is a collar 25 similar to the collar 21 and having a vertical face to contact with 25 the end surface of the roll head 13^b. Projecting from the inner end of the spindle 16 is the usual driving lip or tenon 26 adapted to project into a diametrical groove 27^a in the bottom of the socket 27 in the roll 30 head 13^b, but the arrangement is such that while the inner face of the collar 25 engages the end face of the roll head 13^b, the lip 26 and the adjacent spindle end do not bottom in the socket 27. Thus, it will be understood 35 that when the music roll is inserted between the spindles 15, 16, said spindles will contact only with the end surfaces of the corresponding heads of the music rolls. The collars 21, 25 prevent the spindles from engaging 40 the bottoms of the respective sockets, which is the feature of advantage that is more particularly explained hereinafter. A knurled collar 28 on the spindle 16 facilitates the turning of said spindle by hand so 45 as to engage the lip 26 non-rotatively with the groove 27^a of the socket 27 in the usual manner so that the roll may be driven by the rotation of the spindle 16.

The stem or shaft 16^a is driven by means 50 of suitable connections with an appropriate motor (not shown), which motor is also operatively connected with the shaft or spindles of the take-up roll so as to drive the latter in the usual manner.

55 The music roll selected for illustration is of the standard type used in eighty-eight note players, having relatively shallow sockets in the respective heads thereof. When a roll of this kind is used in the ordinary player piano, the supporting spindles engage the bottoms of the respective sockets. One of the sockets is provided at the bottom thereof with a diametrical groove in the usual manner. When the roll is used with 60 the ordinary form of spindle, a driving lip

engages the bottom surface of this groove. However, while our invention is especially intended to be carried out with this general style of music roll, we do not limit ourselves to such style of roll in all aspects of the 70 invention.

The collars 21, 25 of the respective roll-supporting spindles are yieldingly held in contact with the respective roll heads by mechanism which may be constructed substantially as follows: On the stem or shaft 15^a at a point outside of the spool box are mounted two spaced collars 29, 30, which may be secured on the shaft by means of screws, as shown. Collars 31, 32 are mounted 75 on the shaft 16^a in a similar manner. The collars 29, 31 nearest the spool box are adapted to abut against the respective side walls of the box so as to limit the inward movement of the respective spindles, and 80 these collars are so adjusted that when they contact with the respective walls of the box or other suitable abutments, the collars or shoulders 21, 25 are equidistant from the center of the spool box, and are slightly 85 nearer to each other than are the outer surfaces of the music roll heads. In other words, said collars are spaced apart at a distance which is less than the maximum length of the music roll. Between the collars 29, 90 30, a bar 33 engages the shaft 15^a by means of an inturned end portion 34 which is adapted to abut the collar 29 in order to move the shaft toward the music roll and to 95 abut the collar 30 in order to move the shaft 100 away from the music roll. A similar bar 35 has an inturned end portion 36 embracing the shaft 16^a between the collars 31, 32. The bars 33, 35 are pivoted at 37, 38 respectively to a lever 39 which is swiveled to the back 105 of the box at 40. The swivel mounting 40 of lever 39 is centrally located between the pivots 37, 38 so as to equalize the movement 110 of the two spindles 15, 16 and insure their having a symmetrical relation to a predetermined center line at all times.

In the form shown, the spindles are normally held in their innermost position by means of a spring 41 attached to the music box at 42 and to the lever 39 at 43. When 115 the spindles 15, 16 are moved away from the music roll to free the latter, and then released, the spring 41 returns the parts to the normal position in an obvious manner so that the spindles are at the limit of their 120 inward movement with the collars 29, 31 in abutment with the sides of the box. When a new music roll is to be inserted, the spindles are moved away from each other, for example, by grasping the knurled collar 125 28 on spindle 16, and when the collars 21, 25 of the respective spindles are engaged with the end faces of the roll heads in the manner previously described, it will be found 130 that the note sheet is centered with respect

to the given center line, such as the center line of the music box, because in all music rolls with which we are familiar the center of the note sheet is equidistant from the extremes of the overall length of the roll (engaged by the collars 21, 25), or can be made so if one of the heads or flanges is loosely mounted, and because the spindles are mounted to move equally in opposite directions so as to center rolls of different lengths. The center or longitudinal median line of the note sheet is usually equidistant from the extreme end faces of the roll because the heads or flanges of the roll are of substantially equal thickness and symmetrically formed. One of the most important features of our invention; however, is the positioning of the roll longitudinally of the tracker bar by the overall length of the roll independently of the sockets in the heads or flanges and the projections on the spindles which enter said sockets to support the roll, the arrangement being such that a roll of the kind ordinarily used in eighty-eight note players may be centered in a very simple, effective manner without necessitating any change in the roll construction. It will be understood, therefore, that the roll centering device just described can be used to center music rolls of many different makes without regard to the depth of the sockets in the roll heads so long as such sockets have the usual minimum depth. This is effected by making the socket-engaging projections on the spindles so shallow that they will not engage the bottoms of the sockets of any of the standard music rolls.

If, after assembling, it is found that the spindles do not have the proper symmetrical relation to a predetermined center, the necessary correction can be effected by shifting the shaft collars in an obvious manner. The collars on each shaft should obviously be spaced apart at a sufficient distance to permit the necessary swinging movement of the bars 33, 35. Ordinarily, the center with respect to which the collars 21, 25 are symmetrical is in a vertical plane passing through the center of the tracker bar scale, i. e., the series of perforations in the tracker bar corresponding to the number of notes of the piano which are to be played, but naturally if the tracker bar is to be adjusted out of its normal position, say for the purpose of transposing the key, the music roll will be longitudinally displaced with respect to the tracker bar.

It will be obvious that with the construction described, the collar 21 and projection 22 may be mounted to turn relatively to the main part of the spindle 15 if desired.

The foregoing description is necessarily a detailed one in so far as it concerns the particular embodiment selected for illustration, but obviously we do not limit ourselves

to the precise construction shown, as various changes or modifications may be adopted within the scope of our invention.

In some cases, it might be possible to provide the spindles with yielding tips which are pressed lightly into engagement with the bottoms of the sockets in the roll heads by springs or the like, and this would not be a departure from the broad principles of our invention, even if the spindles did bottom in the sockets in this manner, because the characteristic results of the invention would still be obtained.

We have used the term "centering" in a broad sense as indicating the positioning of the music roll longitudinally with respect to the tracker bar in such a manner that the note sheet will be centered relatively to a given imaginary center line, which may or may not pass through the center of the tracker bar, for the tracker bar may be offset relatively to such center line in transposing, as above suggested. As our invention is based more particularly on the positioning of the roll by its overall length independently of the driving lip or tenon on one spindle and the supporting projection on the other spindle, the equidistant location of the note sheet center with respect to the extremes of the overall length of the roll is not material in the broadest aspects of the invention so long as the music rolls used are similar as regards the disposition of the note sheet center. In other words, if the note sheet center of a given roll be located at different distances from the respective extremes of the overall length of such roll, so that such distances bear a certain unequal ratio to each other, it is merely necessary that such ratio be maintained in the other rolls which it is desired to play on the instrument, although if the note sheet center is not equidistant from the end faces of the roll, the spindles will obviously have to have a differential movement. However, the flanges of a music roll are usually of equal thickness, as above stated, so that this ratio is one to one, and the spindles have an equal movement, as herein explained.

Our improved roll centering mechanism may be used to advantage in connection with the sheet winding mechanism disclosed in our application Serial No. 76,387 filed February 5, 1916, of which the present application is a division, but it is obviously not limited to such use.

What we claim is:

1. In a device for alining tracker bar note openings with the note sheet perforations of a music sheet on any of a series of music rolls each having the respective heads of substantially equal thickness and sockets in said heads, the combination of a tracker bar, spindles for supporting the music roll, roll-positioning parts on the respective spindles

adapted to engage surfaces at the extremities of the roll noncoincident with the sockets, and parts on said spindles adapted to enter the roll sockets, said roll-positioning parts 5 contacting with the coöperating surfaces of the roll to position the roll longitudinally with respect to the tracker bar by engagement with the aforesaid roll surfaces independently of said sockets and the spindle 10 parts entering the same; substantially as described.

2. In a device for alining tracker note openings with the note sheet perforations of a music sheet on any of a series of music rolls having shallow sockets in the heads thereof and a groove in the bottom of one of said sockets, the combination of a tracker bar, spindles for supporting the music roll having shoulders adapted to engage the 15 ends of the music roll outside of said sockets to position the roll longitudinally by contact therewith, one of said spindles having a tenon adapted to engage said groove for driving the roll, and means for maintaining 20 the shoulders on said spindles at equal distances from the same point when different rolls are employed; substantially as described.

3. The combination with a tracker bar, of 30 a music roll having end sockets, and supporting spindles for said roll having projections entering the respective sockets, one of said projections in driving engagement with its corresponding socket, means on said 35 spindles located at and engaging the respective extremes of the overall range of the roll for positioning the roll longitudinally with respect to the tracker bar independently of said projections and said 40 sockets; and means for pressing the spindles against the outer faces of the roll heads; substantially as described.

4. The combination with a music roll having heads and shallow sockets in the outer 45 faces of said heads, of a spindle having a driving projection engaging one of said sockets but spaced from the bottom thereof, a second spindle having a projection engaging the other socket but spaced from the bottom thereof, shoulders on said spindles bearing against the outer faces of the roll heads around the sockets for positioning the roll longitudinally independently of said projections and said sockets, means connecting 50 said spindles whereby they move equally in opposite directions, and means for exerting pressure on said spindles to hold them against the roll heads; substantially as described.

60 5. In a device for alining the note perforations of a music sheet with tracker bar note openings, with any of a series of music rolls having heads of substantially equal thickness and note sheets whose longitudinal 65 median lines are substantially equidistant

from the outer faces of the roll heads, said rolls also having shallow sockets therein and bearing surfaces around said sockets at the extremes of the overall length of said rolls, the combination of longitudinally movable 70 supporting spindles having roll-positioning surfaces for contacting with said bearing surfaces, and projections on the respective spindles constructed and adapted to enter the respective sockets but to clear the bottoms thereof, one of said projections adapted to have driving engagement with the roll within its corresponding socket, and means for moving said spindles equal distances toward each other; substantially as described. 75

6. In a device for alining the note perforations of a music sheet with tracker bar note openings, with any of a series of music rolls having the respective heads of substantially equal thickness and note sheets whose 80 longitudinal median lines are substantially equidistant from the outer faces of the roll heads, the combination with a music roll having heads with sockets therein, one of said sockets having a diametrical groove in 85 the bottom thereof, of longitudinally movable supporting spindles for said roll having supporting means to engage the respective sockets, one of said spindles having a part in driving engagement with said diametrical groove, means on said spindles for engaging the end faces of the roll to position the roll longitudinally relatively to the tracker bar by means of said end faces, independently of said sockets and the supporting 90 means engaging the same, and means for maintaining the surfaces on said spindles, which position the roll longitudinally, at equal distances from an imaginary center line; substantially as described. 95

7. The combination with a music roll having sockets in the heads thereof with annular bearing surfaces around said sockets at the ends of the roll, one of said sockets provided in the bottom thereof with a diametrical groove, said heads being of substantially equal thickness, and the note sheet center being substantially equidistant from the outer faces of the roll heads, of a tracker bar, spindles having supporting means entering said sockets but clear of the bottoms thereof, one of said spindles having a part engaging said diametrical groove but clear of the bottom thereof, and shoulders on the respective spindles engaging the aforesaid 110 annular bearing surfaces around the sockets for centering the roll relatively to a given center line by means of said surfaces and independently of said sockets; substantially 115 as described.

8. In a device for positioning music rolls of different lengths relatively to the tracker bar of a self-playing piano, the combination with a tracker bar, and a music roll, of longitudinally movable spindles having roll- 120 125 130

positioning means engaging the roll at the extremes of its overall length, and means for causing said spindles to assume a symmetrical relation with respect to an intermediate point on the tracker bar when rolls of different lengths are supported thereby; substantially as described.

9. In a device for automatically positioning relatively to the tracker bar of a musical instrument any of a series of music rolls wherein the distance from the note sheet center to one of the extremes of the roll length is equal to the distance from the note sheet center to the other extreme of the roll length, the combination of a tracker bar, a music roll having the respective heads of substantially equal thickness with shallow sockets therein, one of said sockets having a diametrical groove in the bottom thereof, longitudinally movable spindles engaging said sockets to support the roll, one of said spindles having a lip to engage said groove

but clear of the bottom thereof, both of said spindles clear of the bottoms of the respective sockets, roll-positioning portions on said sockets engaging the end faces of the roll adjacent the rims of said sockets at the respective extremes of the roll length to position the roll longitudinally relatively to the tracker bar independently of said sockets, and the socket-engaging portions of the spindles, whereby the note sheet perforations may be caused to register with those of the tracker bar, and means for causing the roll-positioning portions of said spindles to maintain a symmetrical relation to a predetermined intermediate point when rolls of different length are supported by said spindles; substantially as described.

In witness whereof, we have hereunto set our hands on the 27th day of June, 1916.

ERNST D. MOORE.
STANLEY L. FISHER.
